UNITED STATES PATENT OFFICE.

WILLIAM H. SAART, OF ATTLEBORO, MASSACHUSETTS, ASSIGNOR TO THE W. H. SAART COMPANY, A CORPORATION OF MASSACHUSETTS.

DESIGN FOR A CIGAR-HOLDER.

47,437.

Specification for Design.

Patented June 8, 1915.

Application filed January 15, 1915. Serial No. 2,485. Term of patent 3½ years.

To all whom it may concern:

Be it known that I, WILLIAM H. SAART, a citizen of the United States, residing at Attleboro, in the county of Bristol and State of Massachusetts, have invented a certain new, original, and ornamental Design for a Cigar-Holder, of which the following is a specification.

In the accompanying drawings which form a part of this specification, Figures 1,

2, 3 and 4 are front, rear, side, and plan elevations respectively of a cigar holder embodying my new design.

I claim:—

The ornamental design for a cigar holder, as shown.

WILLIAM H. SAART.
